(57) **CLAIM**

The ornamental design for tray for semiconductor devices, as shown and described.

DESCRIPTION

The tray for semiconductor devices is used for holding structures such as semiconductor chips as indicated in phantom. The structures shown in phantom do not constitute an integral part of the disclosure and the claimed design. The tray may be an element of an array formed of a common sheet.

FIG. 1 is a perspective view of a tray for semiconductor devices showing my new design;

FIG. 2 is a top plan view thereof;

FIG. 3 is a front elevational view, the rear elevational view being a mirror image thereof;

FIG. 4 is a right side elevational view, the left side elevational view being a mirror image thereof; and,

FIG. 5 is a bottom plan view thereof.

The broken line showing of the environment is for illustrative purposes only and forms no part of the claimed design.
